BICYCLE CARRIER FOR AUTOMOBILE

Walter Bernard, 4800 S. Lake Park Ave.,
Chicago, Ill. 60615

Filed Dec. 7, 1972, Ser. No. 313,160

Term of patent 14 years

Int. Cl. D12—16; D8—99
U.S. Cl. D12—158

FIG. 1 is a front elevational view of a bicycle carrier for automobile, showing my new design.

FIG. 2 is a side elevational view thereof.

FIG. 3 is a top plan view thereof.

FIG. 4 is a rear elevational view thereof.

I claim:

The ornamental design for a bicycle carrier for automobile, substantially as shown.
